BICYCLE ENGINE

Fred M. Friedlob, Chicago, Ill.

Application July 23, 1949, Serial No. 4,098

Term of patent 14 years

(Cl. D90—8)

To all whom it may concern:

Be it known that I, Fred M. Friedlob, a citizen of the United States, residing at Chicago, in the county of Cook and State of Illinois, have invented a new, original, and ornamental Design for a Bicycle Engine, of which the following is a specification, reference being had to the accompanying drawing, forming a part hereof.

Fig. 1 is a perspective view of a bicycle engine, showing my new design;

Fig. 2 is a top plan view thereof.

I claim:

The ornamental design for a bicycle engine, substantially as shown.

FRED M. FRIEDLOB.
